CLAIM

The ornamental design for a water bottle, as shown and described.

DESCRIPTION

FIG. 1 is a rear, right and top perspective view of a water bottle showing my new design;

FIG. 2 is a rear, right and bottom perspective view thereof;

FIG. 3 is a perspective view thereof with the lid shown separately to show aspects of the design that may not be apparent in the other views;

FIG. 4 is a front view thereof;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof.

The broken lines in the figures illustrate portions of the water bottle that form no part of the claimed design.
